UNITED STATES PATENT OFFICE.

FORREST NAGLER, OF WAUWATOSA, WISCONSIN, ASSIGNOR TO ALLIS-CHALMERS MANUFACTURING COMPANY, OF MILWAUKEE, WISCONSIN, A CORPORATION OF DELAWARE.

HYDRAULIC APPARATUS.

Application filed March 27, 1922. Serial No. 546,995.

To all whom it may concern:

Be it known that FORREST NAGLER, a citizen of the United States, residing at Wauwatosa, in the county of Milwaukee and 5 State of Wisconsin, has invented a certain new and useful Improvement in Hydraulic Apparatus, of which the following is a specification.

This invention relates in general to improvements in the art of converting hydraulic energy, and relates more specifically to improvements in the construction, arrangement and operation of hydraulic machines such as hydraulic turbines and 15 pumps.

An object of the invention is to provide an improved hydraulic machine which is simple in construction and efficient in operation. Another object of the invention is 20 to provide an improved arrangement, setting or association of a plurality of hydraulic turbines whereby a flume of minimum width may be utilized. A further object of the invention is to provide simple and efficient 25 means for propelling centrifugal and similar hydraulic pumps. Another object of the invention is to provide a high-speed high-pressure turbine driven pump in which the turbine and pump are direct connected and 30 wherein the use of speed change gearing is unnecessary. Still another object of the invention is to provide a turbine driven pump unit in which a common source of fluid supply is available to both the pumps and the 35 turbines. A further object of the invention is to provide for automatic balancing in turbine installations. These and other objects and advantages of the present invention will be apparent from the following description. 40 A clear conception of an embodiment of the invention and of the operation of devices constructed in accordance therewith, may be had by referring to the drawing accompanying and forming a part of this 45 specification, in which like reference characters designate the same or similar parts in the several views.

Fig. 1 is a plan view of a turbine driven pump installation.

50 Fig. 2 is a part sectional side elevation of a turbine driven pump installation.

Fig. 3 is an enlarged end view of the turbine inlet structure.

55 Fig. 4 is an enlarged transverse vertical section through the turbine inlet structure.

The hydraulic installation shown in Figs. 1 and 2 comprises in general a plurality of axial-flow high-speed turbine impellers 2 mounted upon a common horizontal shaft 3 directly connecting the impellers 2 with a 60 plurality of high-speed double-suction centrifugal pump impellers 22 which are also mounted upon the shaft 3. The turbine impellers 2 are of the purely axial flow type having relatively high specific speed, such 65 impeller being illustrated and claimed in copending application, Serial No. 197,964, filed Oct. 20, 1917. Each of the turbine impellers 2 receives its supply of actuating 70 fluid through a purely axial flow conduit formed by the casing 23 which comprises an inlet portion 4 and a discharge portion 5. The casings 23 of the impellers 2 are oppositely directed and communicate with a common chamber or source 10 of fluid supply 75 and with a common discharge or tailrace 12. This arrangement produces automatic balancing of the axial pressures on the shaft 3 induced by the impellers 2.

The inlet portion 4 of each casing 23, shown in detail in Figs. 3 and 4, comprises a trumpet shaped annular wall 19, a hub 21 located centrally within the wall 19, and a plurality of stationary guide vanes 18 rigidly uniting the wall 19 and the hub 21. The 80 vanes 18 of each casing portion 4 are spaced axially from the adjacent impeller 2 so as to form a vane free transition space 20 between the guide vanes 18 and the impeller 2, in which space 20 the whirling fluid is 85 permitted to assume a natural whirling motion in order to avoid impact or shock upon entry of the stream to the impeller 2. The cross-section of the guide vanes at their medial portions, is substantially as indicated 90 in the lower half of Fig. 4, the vanes 18 being axially directed at their inlet portions and having their discharge portions inclined oppositely to the direction of inclination of 95 the adjacent impeller vanes. The hub 21 100 provides a bearing for the main shaft 3 directly adjacent to each of the impellers 2.

These discharge casing portions 5 are likewise trumpet shaped as indicated, and are directed toward a vertical wall 6 separating 105 and forming part of the decelerators through which the fluid is delivered from the axially spaced impellers 2. The wall 6 and casings 23 are supported by a hood or wall 17 which separates the common supply 10 from the 110

tailrace 12. The common inlet flume or supply 10 is relatively narrow and receives fluid from the penstock 9 when the gate 11 is raised, the gate 11 serving as the sole means for controlling delivery of fluid to the turbine impellers 2. A by-pass connecting the penstock 9 with the tail race 12 is normally closed by means of a gate valve 16.

The pumping apparatus comprises a pair of double-suction centrifugal pump impellers 22 arranged to receive fluid in series. The impeller 22 of the low pressure pump 7 receives fluid through the suction pipe 13 directly from the common source 10 of fluid supply and delivers fluid through an intermediate pipe 14 to the impeller 22 of the high pressure pump 8. The high pressure pump 8 may deliver the fluid to other pump stages or may deliver the fluid through a discharge pipe 15.

During normal operation of the installation, the gate valve 16 is closed and the gate 11 is opened allowing fluid to enter from the penstock 9 and to substantially fill the common supply chamber 10. From the supply chamber 10 fluid is free to enter the impellers 2 in opposite axial directions through the spaces between the guide vanes 18 and through the transition spaces 20 in advance of the impellers 2. The fluid passing the guide vanes 18 is thereby caused to whirl and passes through the transition spaces 20 and through the impellers 2 in the form of axially advancing whirling streams. The fluid delivered from the impellers 2 retains some of its whirling motion and travels along the discharge portions until it eventually impinges against the opposite sides of the wall 6 whereupon the fluid is deflected outwardly and is substantially completely decelerated. The decelerated fluid drops by gravity into the tailrace 12 from whence it flows by gravity in the usual manner.

The fluid in passing through the turbine impellers 2 imparts rotation to the shaft 3 and to the pump impellers 22 mounted upon this shaft. The rotating pump impellers 22 withdraw fluid from the common supply chamber 10 through the pipes 13, 14 and deliver this fluid under considerable pressure through the discharge pipe 15. It will be obvious that instead of connecting the suction pipe 13 to the supply chamber 10, this pipe may be connected to any other source of fluid supply such as the tail-race 12, but such a connection would require the provision of pump priming means which are not necessary when the chamber 10 is utilized as a supply source.

It will be noted that the arrangement of the turbine impellers 2 and the inlet and discharge conduits thereof, as illustrated, provides an installation which is exceedingly compact and simple, the compactness being the result of admitting the fluid to the in-

10 pellers in axial directions, and the simplicity being due to the elimination of complicated regulating and other mechanism. By utilizing turbine impellers 2 having high characteristics or specific speeds, the centrifugal pump impellers 22 may be directly connected to the turbine impeller shaft, and a pump having high characteristic speeds 15 may be utilized. Such arrangement eliminates the necessity of providing complicated end thrust balancing and regulating means as the impellers 2 balance each other and are always subjected to a constant load thus eliminating danger of attaining runaway speeds. The direct connection also eliminates the use of inefficient transmission gearing such as is necessary when driving high-speed high-pressure centrifugal pumps with the ordinary Francis turbines. By connecting the pump suction pipe 13 to the common 20 supply chamber 10, special priming of the pumps is unnecessary and the entire installation is freely accessible when the main inlet gate 11 is closed. The invention is applicable to vertical or inclined shaft units 25 and to other than turbine driven pump installations.

It should be understood that it is not desired to limit the invention to the exact details of construction and of operation herein shown and described for obvious modifications within the scope of the claims may occur to persons skilled in the art.

It is claimed and desired to secure by Letters Patent:

1. In combination, an impeller through which fluid flows in an axial direction only, means forming an inlet conduit of gradually decreasing cross sectional area approaching said impeller, stationary guide vanes spanning and projecting axially beyond the portion of said conduit having greatest cross sectional area, and means forming a discharge conduit of gradually increasing cross sectional area receding from said impeller.

2. In combination, an impeller through which fluid flows in an axial direction only, means forming an inlet conduit of gradually decreasing cross sectional area approaching said impeller, stationary guide vanes spanning and projecting axially beyond the portion of said conduit having greatest cross sectional area, said guide vanes having inlet guiding surfaces lying in planes parallel to the axis of said impeller and having discharge guiding surfaces lying in planes intersecting said axis, and means forming a discharge conduit of gradually increasing cross sectional area receding from said impeller.

3. In combination, an impeller through which fluid flows in an axial direction only, means forming an inlet conduit of gradually decreasing cross sectional area approaching,

said impeller, stationary guide vanes spanning and projecting axially beyond the portion of said conduit having greatest cross sectional area, said guide vanes being spaced 5 from said impeller and said conduit being free from obstructions at said space, and means forming a discharge conduit of gradually increasing cross sectional area receding from said impeller.

10 4. In combination, an impeller through which fluid flows in an axial direction only, means forming an inlet conduit of gradually decreasing cross sectional area communicating with said impeller, stationary guide

vanes spanning the portion of said conduit 15 having greatest cross sectional area and spaced from said impeller, said guide vanes having inlet guiding surfaces lying in planes substantially parallel to the axis of said impeller and having discharge guiding surfaces lying in planes intersecting said axis and said conduit being free from obstructions between said vanes and said impeller, and a flow decelerator communicating with the discharge of said impeller. 20

In testimony whereof, the signature of the inventor is affixed hereto.
